UNITED STATES PATENT OFFICE

HARRY G. SUTTON, OF SYRACUSE, NEW YORK, ASSIGNOR TO UNITED STATES HOFFMAN MACHINERY CORPORATION, OF NEW YORK, N. Y., A CORPORATION OF DELAWARE

GARMENT PRESS

Application filed May 7, 1929, Serial No. 361,176. Renewed April 28, 1932.

This invention pertains to garment presses and is a continuation in part of my application Serial No. 231,912, filed November 8, 1927. The invention has for its main object the production of a power actuated press which is simple and effective in its operation and withal safe guarded against any possibility of the operator getting his or her hands between the pressing elements when power is being applied.

A further object of the invention is to provide a press wherein the head may be lowered toward the buck by the operator independently of the power mechanism so that the operator can, if he so desires "pat" the goods and be sure that the head is coming down upon the buck with the goods in proper relation to such elements before the final heavy pressure is effected.

Another object is to provide a foot lever for lowering the press head into cooperative relation with the buck, the foot lever having a treadle associated therewith, and a connection between the foot lever and treadle to permit relative upward movement of the treadle with respect to the foot lever. This arrangement removes the danger of injury to the operator's foot when the power mechanism is actuated to apply the final pressure.

In a broad sense the structure may be said to involve the use of a head carrying element which is first drawn to preliminary contacting position by the operator; a constantly operating power mechanism; a hand operated mechanism for throwing the power mechanism into operative relation with the pressing element; and means interposed between said hand operated mechanism and the power mechanism whereby the power mechanism cannot be brought into operative relation until the head is first lowered by the operator to contact the article on the buck and the parts so positioned that the hand operated control mechanism may be actuated and cause the power mechanism to become effective.

The preferred embodiment of the invention is shown in the annexed drawings wherein,

Figure 1 is a side elevation of a press with the head in its fully open position, parts be-

ing broken away and shown in section to more clearly illustrate the structure,

Figure 2 is a similar view with the head in its preliminary lowered position, where it would contact the goods, the parts then assuming such position that the constantly operating power mechanism may be brought into action,

Figure 3 is a top view of the foot lever and treadle,

Figure 4 a transverse vertical sectional view taken on the line IV—IV of Figure 5 illustrating the power mechanism in part and the control mechanism interposed therebetween and the pressure applying toggle associated with the head carrying frame,

Figure 5 a sectional elevation of the power mechanism and the allied parts, and

Figure 6 a top plan view of the power and control mechanisms with the frame of the machine broken away.

In said drawings 1 denotes the bed or frame of the machine provided at its rear with an upwardly extending portion 2. At its forward portion the frame is surmounted by a pedestal 3 carrying the lower fixed pressing element or buck 4, which as will be understood may be of any desired configuration and contour.

The member 2 at its upper end extends inwardly between the side elements 5 and 6 of the head carrying frame or lever, the latter being fulcrumed upon a shaft 7 extending through said members 5 and 6 and the upper end of the member 2.

The head denoted by 8 is attached to the forward end of the head carrying frame or lever and of course will be shaped to conform to the outline and contour of the buck.

A handle 9 extends forwardly of the head being sustained in position by brackets 10, only one of which is disclosed in the drawings.

So far this is the usual press construction.

Pivotedly mounted at the rear of the head carrying lever between the spaced arms 5 and 6 thereof is a swivel block 11 which forms the upper support and connection for an adjustable link or upper toggle member denoted generally by 12. The lower end of said tog-

gle member or link is pivotally attached, as at 13, to the upper end of a second toggle element 14, the latter at its lower end being pivotally secured, as at 15, to the lower portion 5 of the bed plate or frame 1.

A pair of springs as 16, only one of which is shown, is secured to the head carrying lever to the rear of the fulcrum 7, the lower ends of the springs being secured to the base frame 10 1 as is usual in presses of this same general character. These springs tend to swing the head carrying lever so as to move the head from the position shown in Figure 2 to that shown in Figure 1. In other words, they tend 15 to maintain the head in its elevated open position.

As shown in the drawings the lower element 14 of the toggle has a lateral extension 17 to which is pivotally secured the link 18, 20 which in turn connects the toggle with a foot lever 19. The foot lever and link 18 form in effect a secondary toggle member cooperating with the element 14 of the main toggle to close the press when the foot lever is 25 depressed. Lever 19 is fulcrumed on a shaft 20 mounted on bracket 21 secured to the press frame, the forward arm of the lever being relatively short and projecting beyond the front of the press frame but a short distance. 30 Also mounted for pivotal movement about the shaft 20 and supported by the bracket 21 is a treadle member 22 having a forked end portion 23 which straddles the bracket, and a web portion 24 overlying the forward arm of 35 the foot lever. A bumper 25 of rubber or other suitable material is interposed between the treadle and the foot lever, being secured to a boss 26 on the foot lever in the form illustrated in the drawings.

40 It is obvious that with the above construction depression of the treadle will lower the forward end of the foot lever, raise the rear portion of the foot lever and link 18 to straighten the secondary toggle, and at the same time tend to straighten the main toggle mechanism to bring the press head 8 into 45 pressing relation with the buck 4.

For the purpose of applying a final heavy 50 pressure to the pressing head a power operated mechanism is provided. The power mechanism is best shown in Figures 4, 5 and 6. Mounted upon a bracket 27, Figure 5, extending outwardly from the frame of the machine, is a constantly rotating electric motor 55 28, the shaft whereof is interconnected through a flexible coupling of any approved type, designated by 29, with a shaft 30, which latter is supported in suitable bearings formed in or carried by a frame or housing 60 31 likewise supported upon a bracket 32 secured to the bed frame 1.

Shaft 30 has secured to it a worm 33 which is constantly in mesh with a worm gear 34, the hub whereof is splined or keyed to the outwardly extending hub 35 of a bevel or sun- 65

gear 36. Said gear is supported upon a sleeve bearing 37 which finds its support upon a shaft 38, the latter being supported in suitable bearings in the housing. Sun-gear 36 meshes with planetary gears or pinions 39 70 mounted upon spindles 40 extending outwardly from a spindle frame 41 journaled for rotation upon the shaft 38.

Secured to the outer extended ends of the spindles 40 is a ring-shaped frame or member 75 43 preferably formed in two parts, as shown in Figure 4, and bolted together so as to embrace the outer ends of the spindles.

The outer face of the ring-shaped member or frame 43 is provided with a series of teeth 80 44 equally spaced thereabout and underlying a vertically disposed bolt or pin 45 mounted for reciprocation in a bearing formed in the upper part of the housing 31. The lower end of the bolt is slightly tapered so that it may 85 pass between the teeth 44 and hold the frame 43 against rotation. The means for actuating this bolt will be later described.

The mechanism just set forth constitutes, in effect, planetary gearing, it being understood that unless the movement of the spindle frame 41 be arrested no motion will be transmitted to the shaft 38.

Shaft 38 extends inwardly of the main frame 1 and is supported thereby in a bearing 46, Figure 4, and has keyed to its outer end a combined crank disk and cam member 47. Secured to said member is a crank pin 48, the opposite end of the pin being secured in a second crank element 49 which in turn is secured to a stub shaft 50 which is supported in a bearing 51 also mounted in a portion of the fixed frame 1 of the machine.

A crank rod or pitman 52 is connected with the shaft 48 and at its opposite or rear end is 105 pivotally connected as at 53 to the lower toggle element 14.

As will be appreciated, when the frame member 43 is locked against rotation, motion will be imparted to the crank and pitman 110 through the gearing above described. That is to say from worm 33, to worm wheel 34, gear 36, planetary pinions or gears 39 (which then rotate about their spindles 40), sun-gear 42, direct to shaft 38 and thence through the 115 crank comprising the members 47 and 49 to the pitman 52. Thus the toggle may be straightened or broken through the actuation of the power mechanism.

As above indicated, it is desirable that the 120 power mechanism be held ineffective until the head is closed either manually or by the foot lever and to that end of the cam member 47 is employed to prevent the throwing in of the arresting bolt or pin 45.

As will be seen upon reference to Figures 4 and 5, the bolt 45 is provided with an upwardly extending stem 54, the upper end of which is threaded and somewhat reduced. A 130 spring 55 encircles the lower portion of the

stem bearing at its lower end upon a shoulder formed upon the bolt and at its upper end taking against a washer 56 which underlies the forked end of a lever 57, which latter is secured to the outer end of a rock shaft 58. The upper end of the stem 54 passes through the forked end of the lever 57 and a washer and nut 59 are secured to the upper end of said stem and thus hold the parts in their proper assembly.

Lever 57 is normally pressed upwardly by a spring 60 which underlies the same and is seated in a socket formed in the housing 31. A stop arm 61 formed upon the lever 57 carries an adjustable stop screw 61a which co-acts, as will be seen upon reference to Figure 5, with the housing to prevent the lever from being thrown upwardly beyond a predetermined point.

Shaft 58 is journaled in a fixed bracket on the frame 62 and at its inner end has secured to it a lever having arms 63 and 64. Arm 64 overlies a roller 65 carried by a depending lever or arm 66 mounted for oscillation upon a stub shaft 67. Said arm 66 is normally held in its outward position by a spring 66a. A hand lever or rod 68 extends outwardly and upwardly from the lever 66 and is provided with a hand-piece 69 adjacent the forward edge of the table of the press. Arm or lever 66 also carries at its lower end a second roller 70 while lever 63 is also provided with a roller as 71 at its lower end. These two rollers 70 and 71 are designed to cooperate with the combined crank disk and cam member heretofore designated by 47.

As will be seen upon reference to Figures 1 and 2, more particularly, roller 70 cooperates with the outer cam surface 72 while the roller 71 is designed to operate with the internal camway or face 73. The parts are so adjusted and arranged that when the head is in its elevated, or partially elevated position, or anything short of the preliminary contacting position, roller 70 will rest upon the cam surface 72 and depression of the arm 68 and consequently rocking of the lever 66 is inhibited.

In Figure 1 the press is shown as fully open in which position it will be seen that the roller 70 rests upon the cam 72 and hence lever 66 cannot be rocked to actuate the lever 63, 64 through the roller 65. When, however, the head is lowered to contact the buck the parts will come to the position shown in full lines in Figure 2, the toggle approaching the straightened position; this being permitted by the fact that the combined crank disk and cam may be rotated notwithstanding the motor is in operation as the sun-gear 36 merely rotates with reference to the planetary gears and causes the latter to move their supporting frame or spider around the other sun-gear. When the head reaches its preliminary contacting position the parts

then are in the full line position shown in Figure 2. Depression of the arm 68 is then permitted as the roller 70 will swing inwardly over the reduced or cutaway exterior cam surface 72. During such motion the roller 65, bearing against the under face of the lever arm 64 will throw said arm upwardly and as a consequence will rock the shaft 58 clock-wise, thus depressing the outer end of the lever 57 and forcing the bolt 45 downwardly into engagement with the underlying teeth 44 of the ring-shaped frame 43. At the same time lever arm 63 will also be rocked downwardly and the roller 71 come into alignment with the throat of the inner cam surface 73 thereby permitting the combined cam and crank disk to rotate until the crank connection with the disk reaches the point designated as A in Figure 2, at which time the toggle will be fully straightened and full pressure applied to the press. When this position is reached a depression 74 in the interior cam surface will come into alignment with the roller 71 allowing the roller to pass into the same and as a consequence will allow the bolt 45 to be moved upwardly or to move upwardly automatically, if pressure upon the hand-piece 69 is released, and thus arrest further movement of the combined crank disk and cam. Thus the press may be closed under power and the pressure retained. By again depressing the hand-piece 69 the roller 71 will be withdrawn from the depression 74 in the cam surface 73 and the bolt again moved downwardly into engagement with the teeth 44 of the ring frame thus bringing the power train into effective motion and drawing the toggle from its straightened position.

Referring to Figure 2 it will be seen that just prior to the application of heavy pressure by the power mechanism the forward end of the foot lever has been lowered to such a position that there is sufficient space beneath the treadle to permit the operator's foot to be disposed thereunder. Were the treadle rigid with the foot lever it is apparent that further straightening of the main toggle, and incidentally the secondary toggle of which the foot lever is a part, by the power mechanism would force the treadle downwardly still further and injure the operator's foot. The relative movement between the treadle and foot lever in the arrangement described above removes this danger, it being obvious that, although the forward end of the foot lever continues to move down, the treadle merely rests on the operator's foot.

It will thus be seen that the press may be first closed either manually or by the foot lever, that the operator may raise and lower the press head independently of the power mechanism in order to inspect the goods and this without fear of injury to the hands or

feet as the power mechanism is inoperative to effect pressure at such time. If and when he has secured a lay of the goods to his satisfaction he finally draws the head to pressing 5 relation with respect to the buck and the goods imposed thereon and may initiate the application of power by merely depressing the hand-piece 69.

It will be noted that when the toggle is in 10 its fully closed position the center lines of the crank, the crank connection 48 and the pivotal connection 53 are not in alignment. They will be locked in this position so as to maintain the required pressure by entrance 15 of the roller 71 into the depression or cut away portion 74 of the inner cam surface 73. By this arrangement no trouble ensues in unlocking the press as might be the case if the center lines of the connection all are lined up. 20

What is claimed is:

1. In a garment press, the combination of a pair of relatively movable pressing elements, one of said members being freely movable toward and from the other by the 25 operator; a constantly moving power applying mechanism; crank means interposed between said mechanism and said last-named pressing element for applying heavy pressure between the pressing elements; means 30 for effecting an interconnection between said pressure applying means and the power mechanism when and only when the pressing elements have been brought to pressing or closed position; operator controlled means for actuating said interconnecting means; and lock-out means rotatable with said crank means and positioned by the movement of the head for preventing actuation of said operator controlled means until said elements are in 35 40 pressing relation.

2. In a garment press, the combination of a fixed pressing element; a movable pressing elements free to be moved toward and from the fixed element into and out of pressing 45 relation therewith by the operator; constantly operating power means; crank means for applying pressure to the movable pressing element; a connection between said last-named means and the power means, said connection being normally disconnected from the power means; means for connecting the power means to the pressure applying means; operator controlled means for actuating said connecting means; and means rotatable with 50 said crank means and positioned by movement of said movable pressing element to prevent actuation of said operator controlled means until said elements are in pressing relation. 55

3. In a garment press, the combination of a fixed pressing element; a movable pressing element free to be moved toward and from the fixed element into and out of pressing 60 relation therewith by the operator; constantly operating power means; crank means for ap-

plying pressure to the movable pressing element; a connection between said last-named means and the power means, said connection being normally disconnected from the power means; means for connecting the power means to the pressure applying means; operator controlled means for actuating said connecting means; and a stop device rotatable with said crank means and positioned by movement of said movable pressing element 70 for preventing actuation of said operator controlled means until the movable pressing element has been closed upon the fixed pressing element. 75

4. In a garment press, the combination of a fixed pressing element; a movable pressing element free to be moved toward and from the fixed element into and out of pressing relation therewith by the operator; constantly operating power beans; means for applying pressure to the movable pressing element; a connection between said last-named means and the power means, said connection being normally disconnected from the power means; means for connecting the power means to the connection aforesaid and thereby effecting operation of the pressure applying means; operator controlled means for actuating said connecting means; and a rotatable stop device interconnected with and movable by the connection between the power applying means and the power means preventing operation of the last-named operator controlled means until the movable pressing element has been closed upon the fixed pressing 90 element. 95

5. In a garment press, the combination of a fixed pressing element; a second pressing element mounted for free movement toward and from the latter by the operator; toggle 100 mechanism associated with said second pressing element for effecting heavy pressure between the pressing elements; power means; a combined crank disk and a cam; a crank extending therefrom to the toggle; operator operated means for connecting the crank disk and cam to the power means; and means co-acting with the cam to prevent actuation of the operator operated means until the press has been brought to closed position. 110

6. In a garment press, the combination of a fixed pressing element; a movable pressing element free to be moved toward and from the other by the operator; power means; crank means interposed between the latter and the movable pressing element to effect heavy pressure between the pressing elements, said two means being normally disconnected; manually actuated locking means interposed between said two means for connecting said two means; and means rotatable with said crank means and positioned by movement of the movable pressing element for preventing actuation of the latter until 120 125

the movable pressing element is brought to closed position.

7. In a garment press, the combination of a fixed pressing element; a movable pressing element free to be moved toward and from the other by the operator; power means; crank means interposed between the latter and the movable pressing element to effect a heavy pressure between the pressing elements, said two means being normally disconnected; manually actuated locking means interposed between said two means for connecting said two means; means rotatable with said crank and positioned by movement of the movable pressing element for preventing actuation of the latter until the movable element is brought into pressing relation with the fixed element, and means also associated with said crank means and movable therewith for locking of the press in its closed, heavy pressure applying position.

8. In a garment press, the combination of a fixed pressing element; a movable pressing element free to be moved into and out of pressing relation to the other by the operator; a constantly moving power means; crank means interposed between the movable pressing member and the power means for applying heavy pressure to said movable pressing member, said crank means being normally disconnected from the power means; means for producing an interlock between the power means and the crank means aforesaid; operator controlled means for actuating said interlocking means; means rotatable with said crank means for preventing actuation of said operator controlled means until the pressing elements are brought together; means normally tending to disconnect the power means and the crank means; and means on said rotatable means for maintaining the connection between the power means and crank means until maximum heavy pressure has been effected and immediately thereafter releasing the connecting means thereby to allow heavy pressure to be maintained for any desired period.

9. In a garment press, the combination of a fixed pressing element; a movable pressing element; a foot lever for moving said movable element into cooperative relation with said fixed element; power mechanism for moving said movable element; and a treadle member for actuating said foot lever, said member overlying said lever and being mounted for upward relative movement with respect to said foot lever.

10. In a garment press, the combination of a fixed pressing element; a movable pressing element; a toggle mechanism for moving said movable element to closed position; a foot lever connected to said toggle mechanism; a power mechanism connected to said toggle mechanism; and a treadle member for actuating said foot lever, said member over-

lying said lever and being mounted for upward relative movement with respect to said foot lever.

11. In a garment press, the combination of a fixed pressing element; a movable pressing element movable by the operator toward and from the fixed element; a power train associated with the movable element for producing heavy pressure therethrough after the press is closed by the operator; control means for the power train embodying a rotatable cam and a manually actuated interlock for the power train; and means for rotating said cam comprising a connection between the cam and said movable pressing element, said cam serving to prevent actuation of the interlock until said cam is shifted by the operation of closing the head, said cam likewise permitting withdrawal of the interlock when the press is exerting heavy pressure.

12. In a garment press, the combination of a buck; a head; constantly driven planetary gearing; a toggle mechanism; connections between said toggle and the shaft supporting one of the sun-gears of said gearing for straightening the toggle; means under control of the operator for arresting planetary movement of the planetary gears of the gearing and thereby causing rotation of the aforesaid sun-gear; and means controlled as to position by an operator controlled movement of the head toward the buck for preventing actuation of said arresting means until the head is brought to closed position.

13. In a garment press, the combination of a buck; a head; constantly driven planetary gearing; a toggle mechanism; connections between said toggle and the shaft supporting one of the sun-gears of said gearing for straightening the toggle; means under control of the operator for arresting planetary movement of the planetary gears of the gearing and thereby causing rotation of the aforesaid sun-gear; and a cam rotatable with said shaft, said cam being positioned by operator controlled movement of the head toward the buck, and adapted to prevent actuation of said arresting means until the head is brought to closed position.

14. In a garment press, the combination of a buck; a head; constantly driven planetary gearing; a toggle mechanism; connections between said toggle and the shaft supporting one of the sun-gears of said gearing for straightening the toggle; means under control of the operator for arresting planetary movement of the planetary gears of the gearing and thereby causing rotation of the aforesaid sun-gear; and a cam rotatable with said shaft, said cam being positioned by operator controlled movement of the head toward the buck, and adapted to prevent actuation of said arresting means until the head is brought to closed position, said cam being so formed as to allow retraction of said arresting means

when the toggle is exerting its maximum effect.

15. In a garment press, the combination of a buck; a head; constantly driven planetary gearing; a toggle mechanism for exerting pressure upon the head when the latter is in its closed position; a crank disk carried by the shaft of one of the sun-gears of the gearing; a crank extending therefrom and 10 connected to the toggle; an exterior and an interior cam formed upon the crank disk, said interior cam being provided with an outwardly extending portion; a ring-shaped frame mounted upon the supporting spindles of the 15 planetary gears of the gearing; teeth formed thereon; a spring retracted bolt standing in line with said teeth; a lever associated with said bolt and serving when depressed to move the bolt into engagement with the teeth; a 20 second lever movable with said last-named lever, said second lever at its outer end coacting with the interiorly formed cam aforesaid; a third lever fulcrumed upon a fixed portion of the machine, the lower end of said lever 25 coacting with the exterior cam; a roller carried by the third lever and standing in operative relation with the second-named lever to rock the same when the third lever is swung counter-clockwise; and means for rocking 30 said third lever.

16. In a garment press, the combination of a fixed buck; a head mounted for swinging movement toward and from the buck; toggle mechanism for applying heavy pressure to the head when the latter is brought to its closed position; planetary gearing; means for constantly rotating one of the sun-gears of said gearing; a ring-shaped member carried by the spindles of the planetary 40 gears of said gearing; teeth extending outwardly therefrom; a rocker shaft; an arm secured to said rocker shaft; a spring serving to elevate said arm; a bolt associated with the outer end of said arm and standing in line with the teeth; a lever secured to the opposite end of said rocker shaft, the lower end of said lever carrying a roller; a second rocker shaft; an arm extending downwardly therefrom; a roller carried by said arm and standing in operative relation with the upper end of said first-named lever; a handle extending outwardly from the second rocker shaft; a crank disk secured to the shaft of the normally stationary sun-gear of the gearing; a crank extending therefrom to the toggle mechanism; and two cam ways formed upon the disk one exteriorly thereof and the other interiorly thereof, the former cooperating with the lower end of the last-named arm and the latter cooperating with the lower end of the aforesaid lever, the cams being so formed and positioned that operation of the handle and a consequent depression of the bolt to arrest the planetary movement of the planetary 50 gears is prevented until the crank disk has been rotated by a closing movement of the head and the interior cam being so formed as to prevent the entrance of the lower end of the lever into cooperation therewith until the parts assume the relationship just mentioned, said interior cam being likewise formed with an outwardly extending seat or recess which permits elevation of the handle and a consequent retraction of the bolt to permit the parts to come to rest while the toggle is in that position where heavy pressure is applied to the head.

55. In a garment press, the combination of a fixed pressing element; a movable pressing element; a toggle mechanism for moving said movable element into pressing relation with the fixed element; a power mechanism for actuating said toggle mechanism; a second toggle mechanism including a foot lever also adapted to actuate said first mentioned toggle mechanism; and a treadle member for operating said second toggle mechanism, said treadle overlying said foot lever and being 60

disk has been rotated by a closing movement of the head and the interior cam being so formed as to prevent the entrance of the lower end of the lever into cooperation therewith until the parts assume the relationship just 70 mentioned.

17. In a garment press, the combination of a fixed buck; a head mounted for swinging movement toward and from the buck; toggle mechanism for applying heavy pressure to the 75 head when the latter is brought to its closed position; planetary gearing; means for constantly rotating one of the sun-gears of said gearing; a ring-shaped member carried by the spindles of the planetary gears of said gearing; teeth extending outwardly therefrom; a rocker shaft; an arm secured to said rocker shaft; a spring serving to elevate said arm; a bolt associated with the outer end of said arm and standing in line with the teeth; a lever secured to the opposite end of said rocker shaft, the lower end of said lever carrying a roller; a second rocker shaft; an arm extending downwardly therefrom; a roller carried by said arm and standing in operative relation with the upper end of said first-named lever; a handle extending outwardly from the second rocker shaft; a crank disk secured to the shaft of the normally stationary sun-gear of the gearing; a crank extending 80 therefrom to the toggle mechanism; and two cam ways formed upon the disk one exteriorly thereof and the other interiorly thereof, the former cooperating with the lower end of the last-named arm and the latter cooperating with the lower end of the aforesaid lever, the cams being so formed and positioned that operation of the handle and a consequent depression of the bolt to arrest the planetary movement of the planetary 85 gears is prevented until the crank disk has been rotated by a closing movement of the head and the interior cam being so formed as to prevent the entrance of the lower end of the lever into cooperation therewith until the parts assume the relationship just mentioned, said interior cam being likewise formed with an outwardly extending seat or recess which permits elevation of the handle and a consequent retraction of the bolt to permit the parts to come to rest while the toggle is in that position where heavy pressure is applied 90 to the head.

18. In a garment press, the combination of a fixed pressing element; a movable pressing element; a toggle mechanism for moving said movable element into pressing relation with the fixed element; a power mechanism for actuating said toggle mechanism; a second toggle mechanism including a foot lever also adapted to actuate said first mentioned toggle mechanism; and a treadle member for operating said second toggle mechanism, said treadle overlying said foot lever and being 100

100

105

110

115

130

mounted on said foot lever for upward relative movement therewith.

19. In a garment press, the combination of a frame; a fixed pressing element; a movable pressing element; a toggle mechanism for moving said movable element into pressing relation with the fixed element; a power mechanism for actuating said toggle mechanism; a second toggle mechanism also adapted to actuate said first mentioned toggle mechanism, said second toggle mechanism comprising a pair of links pivoted to each other, one of said links being pivoted intermediate its ends to said frame and projecting forwardly of the frame; and a treadle member pivoted to the forward end of said last mentioned link and cooperating therewith to depress the link, said member overlying said link and being movable upwardly relative to said link.

20. In a garment press, the combination of a buck; a head; constantly moving power means; a toggle mechanism; differential gearing interposed between said power means and said toggle mechanism; means under control of the operator for locking one of the gears of said differential gearing to transmit movement from said power means to said toggle mechanism; and means rotatable with one of said gears and controlled by the position of said head for preventing actuation of said locking means until the head is brought to closed position.

In testimony whereof I have signed my name to this specification.

HARRY G. SUTTON.
